(57) **CLAIM**

The ornamental design for offset pliers, as shown and described.

DESCRIPTION

FIG. 1 is a perspective view of the first embodiment of the offset pliers of this design.

FIG. 2 is a front view of the first embodiment.

FIG. 3 is a rear view of the first embodiment of the pliers of this design.

FIG. 4 is a left side elevational view of the first embodiment of the offset pliers.

FIG. 5 is a top view of the first embodiment, with the bottom view being a mirror image of the top view.

FIG. 6 is a right side view of the first embodiment of this design.

FIG. 7 is a perspective view of the second embodiment of the offset pliers of this design.

FIG. 8 is a front view of the second embodiment.

FIG. 9 is a rear view of the second embodiment of the pliers of this design.

FIG. 10 is a left side elevational view of the second embodiment of the offset pliers.

FIG. 11 is a top view of the first embodiment, with the bottom view being a mirror image of the top view.

FIG. 12 is a right side view of the second embodiment of this design.

FIG. 13 is a perspective view of the third embodiment of the offset pliers of this design.

FIG. 14 is a front view of the third embodiment.

FIG. 15 is a rear view of the third embodiment of the pliers of this design.

FIG. 16 is a left side elevational view of the third embodiment of the offset pliers.

FIG. 17 is a top view of the third embodiment, with the bottom view being a mirror image of the top view; and,

FIG. 18 is a right side view of the third embodiment of this design.
